UREA INCLUSION COMPOUNDS OF
n-ALKYL OXIRANES

Bruce W. Brodman, Philadelphia, and Jack Radell, Trevose, Pa., assignors to the United States of America as represented by the Secretary of the Army

No Drawing. Filed May 28, 1964, Ser. No. 371,143

4 Claims. (Cl. 260—96.5)

(Granted under Title 35, U.S. Code (1952), sec. 266)

The invention described herein may be manufactured and used by or for the Government for governmental purposes without the payment to us of any royalty thereon.

This invention relates to new organic compounds and more particularly concerns urea inclusion compounds which are mycologically useful.

Inclusion compounds are a special type of complex. They provide a means by which one compound can be bound with another suitable chemical without changing the chemical character of either. The molecules are unaltered in their chemical nature. The individual compounds may be reconstituted and readily isolated if the

30 drops of n-1,2-epoxyoctane were added to 4.5 ml. of urea-methanol solution (0.15 gram urea per ml. of methanol) in a test tube. The tube was stoppered and shaken for 30 seconds and allowed to stand at 4° C. for 24 hours. The crystals that formed were filtered with suction and washed with 10 ml. of absolute ethanol at 4° C. No crystals formed when the urea-methanol solution was used as a blank. In some cases tetragonal urea crystallized from the urea-methanol solution after a non-complex forming compound had been added.

The dried urea complex was finely ground with a mortar and pestle and applied to the surface of a roughened glass slide. The interplanar spacings and relative intensities were obtained using an X-ray diffractometer with a Geiger tube detector at 35,000 volts and 50 milliamperes with a scanning rate of 1° per minute and the data were recorded.

In preparing our urea inclusion compounds of n-1,2-epoxynonane and n-1,2-epoxydodecane, 30 drops each of the respective samples were used in place of the n-1,2-epoxyoctane.

The following table indicates conclusively the formation of our three novel compounds:

X-RAY POWDER PATTERNS OF UREA INCLUSION COMPOUNDS OF n-R-CH₂-CH₂O

Item No.	n-R	2.06 ^a	2.13-2.18	2.53-2.56	2.62-2.63	2.69-2.70	2.82-2.83	3.01-3.05	3.27-3.28	3.39-3.40	3.56-3.57	3.82-3.87	3.95-4.01	4.11-4.13	4.34-4.37	7.13-7.16

presence of the complexing agent would interfere with the eventual use of the bound material. The complexes may be formed by admixing the reactants in a solvent for one of the compounds, either the host or the guest. Preferably, a mutual solvent is used. A pre-complex formation takes place in solution. Although pre-complexing takes place in most instances by stirring the ingredients at room temperature, dissolution of the materials is often accelerated and oftentimes pre-complex formation may be promoted by the use of elevated temperatures up to about 60 to 70 degrees C.

We have discovered that certain members of the oxirane group, which are known to possess mycological properties, may be trapped and stored as a guest molecule in a urea inclusion compound.

Accordingly, it is a broad object of this invention to provide new urea inclusion compounds.

Another object of the invention is to provide such compounds wherein the included, stored or trapped molecule is an n-alkyl oxirane.

Still another object of the invention is to provide urea inclusion compounds wherein the stored mycologically active molecules are slowly released in a humid atmosphere.

Other objects and advantages of the invention will be apparent as the description of the invention proceeds.

Certain members of the oxirane group are known to be mycologically active. In accordance with our invention we have found that n-1,2-epoxyoctane, n-1,2-epoxynonane and n-1,2-epoxydodecane are capable of being trapped within a urea molecule. Under proper conditions of relative humidity, the host urea molecules are dissolved by the moisture to permit liberation of the trapped oxirane molecule.

In the actual preparation of one of our novel compounds, a urea inclusion compound of n-1,2-epoxyoctane,

From the above X-ray diffraction data, it may be concluded that n-1,2-epoxypentane and n-1,2-epoxyheptane (Items No. 1 and 2) failed to form urea inclusion compounds since the relative intensities at the interplanar spacing 3.95-4.01 Å. indicate uncomplexed urea. Dissociated or tetragonal urea was identified by the presence of a spacing at 3.95-4.01 Å. which is the most intense spacing for urea. In addition interplanar spacings for urea occur, in decreasing order of importance at: 3.01-3.05, 2.13-2.18, 2.82-2.83 and 2.53-2.56 Å. The higher the relative intensity of the spacing for tetragonal urea, using 3.95-4.01 Å., the more dissociated urea is present and the less stable is the complex. Therefore, the stability of a complex contaminated with dissociated urea is inversely proportional to the intensity of the spacing in the X-ray powder pattern for tetragonal urea when prepared as described.

Spacings characteristic of complex formation in decreasing order of importance are: 4.11-4.15, 7.13-7.16, 3.39-3.40, 2.62-2.63, 2.06, 3.27-3.28, 2.69-2.70 and 4.34-4.37 Å. The interplanar spacing at 3.56-3.57 Å. is ambiguous being characteristic of both dissociated urea and complex. These spacings with minor variations have been found to be characteristic of all other urea inclusion compounds studied.

The intensity of the 3.95-4.01 Å. spacing characteristic of dissociated urea which first appears with the n-1,2-epoxyoctane (Item No. 3) complex, rapidly diminishes and disappears as we proceed to the complexes of the higher homologues. n-1,2-epoxynonane (Item No. 4) shows only a slight (0.06) relative intensity for urea and n-1,2-epoxydodecane shows none. Although the corresponding n-1,2-epoxydecane and n-1,2-epoxyundecane were not available, their complexes could safely be predicted to be free of urea since, without exception, the complexes of the higher homologues of any series

studied which formed complexes were more stable than all smaller homologues.

We claim:

1. A urea inclusion compound consisting of a complex of urea and a member of the group consisting of n-1,2-epoxyoctane, n-1,2-epoxynonane, and n-1,2-epoxydodecane.

2. A compound according to claim 1 wherein said member is n-1,2-epoxyoctane.

3. A compound according to claim 1 wherein said member is n-1,2-epoxynonane.

4. A compound according to claim 1 wherein said member is n-1,2-epoxydodecane.
